(57) **CLAIM**

The ornamental design for display screens with graphical user interface with widget, as shown and described.

DESCRIPTION

FIG. 1 is a front view of the first image in a sequence for a display screen with graphical user interface with widget

FIG. 2 is a front view of the second image thereof.

FIG. 3 is a front view of the third image thereof.

FIG. 4 is a front view of the fourth image thereof.

FIG. 5 is a front view of the fifth image thereof; and,

FIG. 6 is a front view of the sixth image thereof.

The appearance of the design transitions sequentially between the images shown in FIGS. 1-6. The process or period in which one image transitions to another forms no part of the claimed design.

The broken line showing of a consumer electronic device, display screen, icons, and other elements of the graphical user interface are included for illustrative purposes only and form no portion of the claimed design.
